UNITED STATES PATENT OFFICE.

OSCAR KATZENBERGER, OF CHICAGO, ILLINOIS, ASSIGNOR TO LAWSON MANUFACTURING COMPANY, OF CHICAGO, ILLINOIS, A CORPORATION OF ILLINOIS.

PIVOT SPRING-HINGE.

1,383,815.

Specification of Letters Patent. Patented July 5, 1921.

Application filed June 12, 1918, Serial No. 239,597. Renewed May 2, 1921. Serial No. 466,217.

To all whom it may concern:

Be it known that I, OSCAR KATZENBERGER, a citizen of the United States, and a resident of Chicago, in the county of Cook and State of Illinois, have invented a new and Improved Pivot Spring-Hinge, of which the following is a full, clear, and exact description.

This invention relates to spring hinges and has for an object the provision of an improved pivot spring hinge which may be used for double swinging doors located at various places and for various purposes, without injuring the door or the support and with assurance that the door will act in the manner desired.

A further object of the invention is to provide a spring hinge for a door which does not require expertness in mounting, while at the same time presenting a sure adjustment for producing a proper alinement.

A still further object of the invention is to provide a box or other support associated with pivots and a spring driving mechanism adjustably connected to one of said pivots whereby the door is allowed the freedom of movement provided by the pivots while caused to return to a given position by the spring mechanism.

In the accompanying drawings:

Figure 1 is a top plan view of a hinge embodying the invention, the same being shown secured to a door and an adjacent support.

Fig. 2 is a side view of the structure shown in Fig. 1.

Fig. 3 is a bottom plan view of the structure shown in Fig. 2.

Fig. 4 is a longitudinal vertical section on an enlarged scale of the lower hinge member shown in Fig. 2.

Fig. 5 is a transverse horizontal section through Fig. 4 on line 5—5.

Fig. 6 is a fragmentary view showing the pintle and spring connections associated therewith.

Referring to the accompanying drawings by numerals 1 indicates a support of any desired kind, as for instance one of the marble slabs in a lavatory while 2 indicates a door of the common double swinging type. It

is, of course, understood that the hinge structure could be used in connection with office partitions, lavatories, office gates, and other places without departing from the spirit of the invention. A pivot pin 3 is arranged at the upper part of the door, said pin being formed integral with plate 4 or rigidly secured thereto, said plate in turn being held in place by suitable fastening means, as for instance screws 5. Pin 3 extends through an aperture in the overhanging shoulder 6 of the box 7. Box 7 is provided with a side plate 8 and face plate 9, said face plate having integral lugs 10 and 11 for receiving suitable screws 12 and 13 extending through the clamping plate 14. Grooves or notches are provided in the support 1 for receiving the lugs 10 and 11 and also the screws 12 and 13 as shown in Figs. 2 and 5.

A box 15 is provided at the lower part of the support 1 so that the lower end of the door will rest thereon, said box being similar in construction to box 7. Preferably an overhanging shoulder 16 is provided with a tapering socket 17 as shown in Fig. 4 for accommodating the tapering end 18 of the pin 19. Pins 3 and 19 are in alinement so that the door will properly swing when it is used. The pin 19 is provided with an upper round section 20 fitting into the socket 21 in casing 22, which acts as a bearing therefore while the central part is provided with an upstanding lug 23 extending longitudinally of the pin as shown in Fig. 6, said lug coacting with the shoulders 24 and 25 on the tension plates 26 and 27. These tension plates are rotatably mounted on the pin 19 and are each provided with a plurality of apertures 28 for receiving the respective ends 29 and 30 of the spring 31. Ordinarily the spring 31 is set to hold the shoulders 24 and 25 against the lug 23 and when either of the tension plates 26 and 27 is moved away from the lug 23 the spring will be brought under further tension so that it will act to return the members to their former position. The pin 19 is held stationary by fitting snugly in the tapering socket 17 in which it is firmly clamped by clamping screw 32 acting on the washer 33 whereby the pin is rig-

idly fixed in place when the parts are properly adjusted. In order to transfer the strain of spring 31 from the plates 26 and 27 to the door 2 casing 22 is provided with a 5 lug 34 (Figs. 4 and 5) said lug acting on the shoulders 35 and 36 of plates 26 and 27 as shown particularly in Figs. 4 and 5. In this construction and arrangement, whenever the casing 22 is rotated either the top plate 26 10 will be moved or the bottom plate 27 and will consequently bring the spring under greater tension. The casing 22 is secured to the door 2 by any suitable means, as for instance by the extension 37 which is prefer- 15 ably made integral with the casing 22 though it may be made separately and rigidly secured thereto. The extension 37 is rigidly secured to the door by any suitable means, as for instance by screws 38. A bot- 20 tom covering member 39 is secured to casing 22, said covering member causing the casing 22 to be substantially dust-proof, while at the same time acting as a support for the lower plate 36. When the door 2 is opened 25 in one direction one of the plates connected with the spring 31 presses against the rib or bar 34 and when the door swings in the opposite direction the other plate connected with the spring presses in the opposite di- 30 rection on rib or bar 34. When it is desired to have the door 2 in direct alinement with the support 1 the lug 23 is arranged opposite lug 34 as shown in Fig. 5, whereby the spring continually tends to bring the door back to 35 a proper alinement. In case it is desired that the door should stop at any point on either side of the position shown in Fig. 5, screw 32 is loosened and the door raised slightly so that the pin 19 may be rotated to 40 any desired extent, after which the screw 32 is again tightened and the device is in position for properly returning the door to the new position when moved therefrom.

Boxes 7 and 15 have been shown and de- 45 scribed because the hinge has been shown connected to a lavatory partition, but it will be evident that other forms of supporting connections may be provided without departing from the spirit of the invention, 50 whenever desired, as for instance office gates. These boxes are desirable for marble slabs and also the support 40 is usually positioned so as to prevent an ordinary box or connection to be provided. It will be noted that 55 the box 15 as well as the box 7 is provided with a neck or extending portion 41 which affords the support 40, while allowing the clamping bolts 42 to be placed the desired distance back from the edge of the support 1.

60 What I claim is:

1. A pivot spring hinge comprising a pivotal pin having a tapering lower end, a connecting member for connecting the pivotal pin with a support, said connecting member having a tapering aperture for receiving

the tapering end of said pin, said pivotal pin having a threaded socket on the tapering lower end, a clamping threaded member en- 70 gaging said threaded socket for drawing the tapering lower end of said pin into said tapering aperture, said threaded member of said tapering lower end permitting an ad- 75 justment of the pin for securing a desired alinement, a lug extending from said pin, a plate loosely mounted on said pin adjacent 75 each end, each of said plates having shoul- 80 ders facing in opposite directions, the shoul- 85 der on one plate engaging one side of said lug and the shoulder on the other plate en- 90 gaging the opposite side of said lug, a spring 95 surrounding said pin with one end project- 100 ing into one of said plates and the opposite end projecting into the opposite plate, a cas- 105 ing adapted to be connected to a door, a projection extending from said casing, and 110 means on each of said plates overlapping said projection, said overlapping means en- 115 gaging said projection on opposite sides whereby the said door is normally held in a given position and moved back by said 120 spring when moved therefrom.

2. A pivot hinge comprising a supporting structure, adapted to be connected with a door, said supporting structure having a pivot pin and a supporting box for engag- 95 ing a support, said box having an arm formed with an opening for receiving said pin, a face plate for engaging flatwise said support and a side plate integral therewith, a pair of lugs extending from said face 100 plate, an adjustable side plate, screw mem- 105 bers extending through said adjustable side plate into said lugs, and a bolt arranged on the opposite edge of said side plates from said lugs and extended through the side plates. 110

3. A pivot spring hinge comprising a piv- 115 otal pin having a lug extending longitudinally thereof and falling short of the ends, a stationary support connected with one end of said pin, a casing having a socket fitting over the opposite end of said pin, said casing being adapted to support a door, a project- 120 ing web extending from one end of said cas- 125 ing to the other parallel with said lug, a pair of plates surrounding said pin having pro- 130 jections overlapping said web engaging op- 135 posite sides thereof and shoulders engaging opposite sides of the lug on said pin, and a coiled spring having one end secured to one of said plates and the opposite end secured to the other of said plates.

4. A pivot hinge of the character de- 125 scribed comprising an upper pivot member, a pivot pin, means for connecting the same with a door, a stationary support having a 130 part surrounding said pivot pin, a lower pivot pin arranged in line with the upper pivot pin, a stationary support therefor being rigidly secured thereto, a casing for said lower pin engaging said door for supporting 135

the same, said casing resting on said last mentioned pivot pin, a lug projecting from said last mentioned pivot pin, a projecting web extending from said casing, a pair of plates loosely surrounding said pivot pin having overlapping projections engaging opposite faces of the projecting web on the

casing, a pair of oppositely positioned shoulders engaging the opposite sides of the lug on the pin, a coiled spring having the opposite ends connected with said plates, and means for varying the alinement of said door.

OSCAR KATZENBERGER.
